UNITED STATES PATENT OFFICE

148,893

DESIGN FOR A PEDESTAL

Frank Tatar, Cincinnati, Ohio, assignor to Berwyn Lamp & Shade Manufacturing Co., Cincinnati, Ohio, a corporation of Ohio

Application April 24, 1947, Serial No. 138,579

Term of patent 3½ years

(Cl. D29—23)

To all whom it may concern:

Be it known that I, Frank Tatar, a citizen of the United States, residing at Cincinnati, in the county of Hamilton and State of Ohio, have invented a new, original, and ornamental Design for a Pedestal, of which the following is a specification, reference being had to the accompanying drawings, forming part thereof.

Fig. 1 is a perspective view of a pedestal showing my new design.

Fig. 2 is a perspective view of the pedestal of Fig. 1 turned ninety degrees.

The design illustrated is duplicated on the opposite faces of the pedestal.

I claim:

The ornamental design for a pedestal, as shown and described.

FRANK TATAR.
